UNITED STATES PATENT OFFICE.

OSCAR A. HANSZEN, OF DALLAS, TEXAS.

BUILDING-SLAB.

1,375,045.

Specification of Letters Patent. Patented Apr. 19, 1921.

Application filed February 11, 1920. Serial No. 357,923.

To all whom it may concern:—

Be it known that I, OSCAR A. HANSZEN, a citizen of the United States, residing at Dallas, in the county of Dallas and State 5 of Texas, have invented certain new and useful Improvements in Building-Slabs, of which the following is a specification.

This invention relates to new and useful improvements in building slabs for constructing upright walls.

The aim of this invention is to provide a slab or unit which may be utilized in constructing a wall in which vertical flues or air spaces will be present, and to embody 15 in such a slab certain particular features, whereby the slab may be easily and inexpensively produced and a wall constructed of said slabs without elaborate forms thereby reducing the cost of construction and 20 eliminating a considerable usage and waste of lumber. Another feature is to provide a slab of such a nature that when a plurality are assembled in a wall, those on one side may be insulated from those on the 25 opposite side.

In carrying out the invention a slab is formed of plastic material such as concrete, terra cotta or other suitable material and is provided with a rough or finished outer face. 30 On its rear or inner side the slab has a longitudinal sump or channel; while the vertical edges of the slab are beveled outwardly from its face. In constructing a wall the slabs are superimposed in vertical columns 35 and said slabs are disposed with their inner sides or backs in registration, whereby the sumps form vertical air flues or spaces and the beveled edges provide mortar seats or joints which exhibit in cross-section, a dove- 40 tail shape, between the edges of adjacent slabs on each side of the wall. Other features will hereinafter be brought out.

The invention will be more readily understood from a reading of the following specification and by reference to the accompanying drawings, in which an example of the invention is shown, and wherein:

Figure 1 is a view showing a portion of a wall constructed with slabs embodying this 50 invention, and

Fig. 2 is a view of the upper portion of one of said slabs.

In the drawings the numeral 10 designates a slab which while preferably formed 55 of a plastic material may be made of any

material suitable for the purpose for which the slab is to be used. The slab may have a smooth face or outer side 11 or this face may be formed to embody some particular design or configuration.

It is preferable to give the slab a greater length than width but this is not essential, although it makes a better design where the slabs are arranged in upright columns. The slab has in its rear or inner side a longitudinal sump or channel 12 extending its entire length and having such a width as to provide outwardly directed flanges 13 along each vertical edge of the slab. Each vertical edge or end 14 of the slab is beveled 60 outwardly and rearwardly from the face 11. It is pointed out that the degree of the angle of this bevel may be varied as the conditions may require and the particular angle shown in the drawings is merely an 65 exemplification. It is obvious that the slab could be formed by pressing in a suitable mold or by pouring a mixture into a suitable mold.

In constructing a wall the slabs are placed 70 with their backs together so that the flanges 13 of the slabs on one side of the wall register with the flanges 13 of the slabs on the other side of the wall and the faces 11 form the outer sides of the wall as is shown in 75 Fig. 1. The slabs are superimposed in vertical columns and may be in break-joint relation. It will be seen that the registering sumps 12 form vertical air flues and by coating the rear edges of the flanges 13 with 80 tar or other water proofing material, an insulated construction is had.

The slab columns are spaced apart and 85 mortar 15 is inserted in the spaces. The beveled edges 14 of adjacent slabs on each side of the wall form dove-tail seats for the mortar and the seats on one side being connected with those on the other side form a lock whereby each mortar strip 15 becomes 90 a key. By this arrangement mortar keys 100 each flaring outward in both directions from its center, are provided and the lateral displacement of the slabs precluded. In constructing such a wall it is merely necessary to provide guides and strips on each side 105 of the mortar joints. This does away with the use of a large quantity of lumber usually employed in erecting forms and thus expense and waste are eliminated to a great extent by the use of this slab. It is possible 110

to cast the slabs so that their faces 11 will be smooth without troweling and paint may be applied directly to such faces.

What I claim, is:

- 5 A wall comprising vertical sets of blocks, each block in each set comprising a pair of opposed slabs, each slab being provided at its vertical edges with inwardly directed lateral flanges, the flanges of the two slabs
10 forming an air opening in the block, said flanges of each slab having their outer faces converging toward the outer face of the slab, the flanges at each vertical edge of the block

being spaced from the flanges of the adjacent block in the next set forming a space 15 extending from one side of the block to the other, said space having a central contracted portion and diverging in opposite directions toward its free ends, and a column of plastic material molded in said space and 20 having a similar shape in horizontal cross section, said column having its opposite sides terminating substantially flush with the opposite faces of said blocks.

In testimony whereof I affix my signature. 25

OSCAR A. HANSZEN.
